CAP CLOSING TOOL

Joseph F. Esch, Port Neches, Tex., assignor to
The Texas Company, New York, N. Y., a corporation of Delaware

Application May 4, 1933, Serial No. 669,291

3 Claims. (Cl. 113—24)

This invention relates to an improved portable cap closing tool for applying permanent closure caps to cans or drums having relatively large openings, the apparatus being primarily designed 5 for uniform operation so as to prevent defective seals.

The invention is particularly applicable for attaching cup-shaped metal caps in corresponding 10 openings in metal drums used for asphalt and like products where the caps and drums are made of heavy metal requiring a tight seal and one which will withstand substantial pressure.

The above and other objects will appear more fully from the following description when considered in connection with the drawings in which:

Fig. 1 is a plan view of one form of the complete cap attaching apparatus.

Fig. 2 is an elevational view thereof.

Fig. 3 is a vertical sectional view through the 20 apparatus on the line 3—3 of Fig. 1.

Figs. 4 and 5 are detailed views illustrating successive steps in the crimping and flanging of a cap in position on a drum head.

The apparatus includes an expander plate 6 shaped to conform generally to the shape of the cap C which is to be applied to the drum head D. The plate 6 is in the form of an inverted cup with a cylindrical side wall terminating in a circumferential head 6a. The plate is formed at its 25 central portion with an upstanding spindle shank 7 for supporting the operating elements of the tool. The plate is provided with a friction device for preventing movement of the plate over the surface on which it rests. This may be provided 30 by securing a leather or rubber disk 8 within the hollow base of the plate as shown.

The operating mechanism for the seaming tool includes a seaming roller 10 rotatably mounted on the lower end of lever 11. This lever is pivotally mounted, as indicated at 12, on an arm 13, rigidly mounted on a centrally disposed sleeve 14 supported for rotation by means of the roller bearings 15, on the hub or spindle 7 on the expander plate 6. The roller bearings may be of the usual type, the cones and rollers being held in place as by means of an assembly bolt 9. The angular position of the lever 11 and the corresponding position of the seaming roller 10 with respect to the expander plate 6 is controlled by 45 the cam follower 16 rotatably mounted on the upper end of lever 11 and which coacts with a rotatable cam 18 attached to a gear wheel 20 mounted for rotation on the sleeve 14.

Rotation of the cam 18 is accomplished during 50 rotation of the sleeve 14 by means of the large

gear 22 which meshes with the gear 24 formed on the spindle 7, the gear 22 being supported on the hub of a small gear 26, which has a bearing supporting the same for rotation on a rigid arm 28 formed on the sleeve 14. The gear 26 meshes with an intermediate gear 30 which in turn meshes with the gear 20 connected to the cam 18. Power for rotating the sleeve 14 and the arms 13 and 28 carried thereby is through the power drive shaft 32 supplied with a suitable motor or other power or manual operating member (not shown).

The above described apparatus operates as follows:

On rotation of the drive shaft 32 the sleeve 14 is correspondingly rotated, carrying with it arms 13 and 28. During this rotation the expander plate 6 is seated within the cap C as shown in Fig. 4. During the initial rotation the seaming roller 10 is spaced from the periphery of the plate 6 a sufficient distance to accommodate the thickness of the metal forming the cap and drum head, the cam 18 and cam follower 16 remaining in contact in the relative positions shown in Fig. 1, due to positioning of pin 12 beneath the center of mass of lever 11. As the shaft 32 is rotated in the direction of the arrow, that is, clockwise, as viewed in Fig. 1, the seaming roller is moved with the sleeve 14 about the stationary plate 6, the cam 18 being rotated with the sleeve 14 and also turned slowly in a clockwise direction with respect to the cam follower 16. The result is that the lever 11 is gradually tilted to the position shown in Fig. 4 and then to the position shown in Fig. 5, wherein the projecting flange 6a on the plate 6 expands the metal of the cap beneath the body of the drum head at the same time that the upper flange on the drum cap is rolled tightly against and clinched on the upwardly bent flange on the drum head.

It will be seen that during operation the mechanism simultaneously rolls the outside cap seam and expands the lower part of the cap into the drum. The presence of the friction pad 8 and the size of the expander plate 6 prevent any tendency of the plate to turn in the cap being applied.

In the form of the apparatus disclosed herein the parts are so constructed and related as to produce one complete revolution of the cam 18 past the cam follower 16 for approximately forty-one revolutions of the drive shaft 32 and seaming roller 10 as it has been found that this relation of the parts produces a satisfactory seal for the large drum caps with which the apparatus is designed to be operated. It will be understood that the exact sizes and relation of parts as disclosed

are not essential to the operation of the apparatus but under other conditions smaller or larger numbers of rotations of the drive shaft for one operation of the cam would be permissible and in fact more than one cam surface may be provided at 18 if, for example, relatively softer metal is provided for the drum cap or head.

Obviously many modifications and variations of the invention, as hereinbefore set forth, may be made without departing from the spirit and scope thereof, and therefore only such limitations should be imposed as are contained in the appended claims.

I claim:

15. 1. A capping apparatus comprising a stationary expander plate, a power member supported thereon and rotatable with respect thereto, a crimping tool, means for rotating said crimping tool during rotation of said power member and means including a stationary gear carried by said expander plate for automatically controlling the position of said crimping tool with respect to said expander plate during rotation of said power member.

2. A capping apparatus comprising a stationary expander plate, a power member supported thereon and rotatable with respect thereto, a crimping tool, means for rotating said crimping tool during rotation of said power member, means 5 including a stationary gear carried by said expander plate and a gear supported by and rotatable with said power member for controlling the position of said crimping tool with respect to said expander plate during rotation of said power 10 member.

3. A capping apparatus comprising a broad expander plate adapted to be received in a large cap to be applied to a drum head, a stationary spindle shank formed on said plate and projecting upwardly therefrom, a power member rotatably supported upon said spindle shank, a crimping tool rotatable with said power member and means comprising power transmitting gearing carried by said power member and a non-rotatable gear 20 mounted on said shank for moving said crimping tool toward said expander plate during operation of said power member.

JOSEPH F. ESCH.
